UNITED STATES PATENT OFFICE.

HILMA C. CHRISTENSEN, OF SUMMIT, NEW JERSEY.

LADY'S UNDERGARMENT.

Application filed August 31, 1928. Serial No. 303,203.

The invention relates to ladies' undergarments of the type commonly known as a "teddy", in which short front and rear skirt portions are connected detachably with each other between the user's legs and hang loosely around the latter, and it is the object of said invention to provide a new and improved connection between the front and rear skirt portions of the garment.

With the foregoing in view, the invention resides in the novel subject matter hereinafter described and claimed, description being accomplished by reference to the accompanying drawing.

Fig. 1 is a perspective view illustrating the front and rear skirt portions disconnected from each other.

Fig. 2 is a perspective view of the garment as worn.

Fig. 3 is a fragmentary perspective view showing the tab of one of the skirt portions disconnected from the other portion.

Fig. 4 is a fragmentary perspective view looking in the opposite direction from Fig. 2.

Fig. 5 is a vertical sectional view on line 5-5 of Fig. 2.

The garment illustrated comprises a body-encircling portion 6 having shoulder straps 7, and a short full skirt portion 8 to hang loosely and provide the equivalent of drawers legs, when its front and rear portions 9-10 are connected with each other as shown in Figs. 2 and 5.

The skirt portion 9 is provided at its lower end with a tab 11 to turn upwardly against the outer side of the skirt portion 10, appropriate means such as a button 12 and but-

ton-hole 13 being provided for fastening the parts 10-11 detachably together.

The skirt portion 10 is provided with a relatively narrow tab 14 for passage through a slot 15 in the skirt portion 9, said tab 14 being turned upwardly after passage through said slot and secured against the outer side of said skirt portion 9 by appropriate fastening means such as a button 16 and a button-hole 17.

The novel construction shown and described provides an effective closure, and the front and rear skirt portions will not entirely separate from each other, even if the fastening means of one of the tabs 11-14, becomes loosened or damaged.

The details disclosed are preferably followed, but within the scope of the invention as claimed, variations may be made. If desired, the tab 14 and contiguous portion of the skirt part 10, may be provided with an appropriate reinforcement such as 14a.

I claim:

In an undergarment, short front and rear skirt portions, each of said portions having an upturned tab at its lower end lying against the outer side of the other portion, one of said portions having a slot through which the upturned tab of the other portion passes, and front and rear fastening means detachably securing the upturned tabs of the front and rear skirt portions to the rear and front skirt portions respectively.

In testimony whereof I have hereunto affixed my signature.

HILMA C. CHRISTENSEN.
